UNITED STATES PATENT OFFICE.

RUDOLF HUG, OF CINCINNATI, OHIO.

IMPROVEMENT IN LAWN-SPRINKLERS.

Specification forming part of Letters Patent No. 172,024, dated January 11, 1876; application filed October 13, 1875.

To all whom it may concern:

Be it known that I, RUDOLF HUG, of Cincinnati, Hamilton county, State of Ohio, have invented an Improvement in Lawn-Sprinklers, of which the following is a specification:

My invention relates to the class of lawn-sprinklers having jets in revolving arms swiveling upon a fixed pipe supported by a stand upon the ground; and my invention consists, first, in a certain manner of attachment of the nozzles and deflecting-plates at the ends of the arms, by which the arms are rendered conveniently reversible; second, in a peculiar construction of the joint between the revolving arms and the fixed pipe, by which a lessening of friction is effected.

Figure 1 is a perspective view of a lawn-sprinkler embodying the principal parts of my invention. Fig. 2 is a section of the swivel-joint. Fig. 3 is a side view of the swivel-joint. Fig. 4 is a perspective view of one of the extensible legs of the stand. Fig. 5 is a section of the nozzle.

A is the stand or tripod. B is the fixed pipe, and D D' the revolving arms. At the ends of each arm a collar, d, is provided, and screw-threaded end d' for the reception of the nozzle E, to which the deflecting-plate F, which receives the jet of water obliquely for the purpose of giving motion to the arms, is firmly attached. Between the nozzle E and the collar d a compressible or removable washer, G, is introduced, which permits the nozzles to be changed to face its plate F in either direction, so as to give either direction of motion to the arms. The legs of the tripod are in two parts, a a', one being fitted with a

guide-screw, c, and securing-screw e, which pass through a slot, f, in the other.

By the release of screw e, the leg can be lengthened or shortened, the screw c serving as a guide for its motion, and when adjusted it can be resecured by the screw e.

The swivel-joint is composed as follows: The fixed part g has a cross-bar, h, on each side of which the water passes. The revolving part i has also a similar cross-bar, j, having a projecting center-point, k, running in a center depression, as shown, in the bar h, and carrying the weight of the revolving arms on this point, so as to reduce the friction to the minimum. The revolving piece is secured in place by the collar l and lock-nut m, and the nut n secures the arms when they are not required to revolve, and can be used as a broad projecting bearing-surface during revolution, to relieve the supporting-center k of side strains.

I claim—

1. The combination of the collared screw-threaded end d d', washer G, and the reversible nozzles E F, constructed and operating substantially as and for the purpose specified.

2. The combination of fixed part g, having centrally-recessed bar h and revolving part i, with bar j, provided with central pivot point k, the parts being connected and operating substantially as and for the purpose specified.

In testimony of which invention I hereunto set my hand.

RUDOLF HUG.
